PROSTHETIC GENITAL DEVICE

Charles A. Cray, 4801 Eastwick Drive,
Toledo, Ohio 43604

Filed Apr. 19, 1972, Ser. No. 245,688

Term of patent 14 years

Int. Cl. D24—99
U.S. Cl. D83—1 R

FIG. 1

FIG. 2

FIG. 3

FIG. 4

FIG. 5

FIG. 1 is a perspective view of an appliance embodying my new design;

FIG. 2 is a front view of the appliance illustrated in FIG. 1;

FIG. 3 is a side elevation view thereof;

FIG. 4 is a top view thereof; and

FIG. 5 is a sectional view taken along line 5—5 of FIG. 2.

I claim:

The ornamental design for a prosthetic genital device, substantially as shown and described.
